UNITED STATES PATENT OFFICE.

MAURICE J. ACHOR, OF MARION, INDIANA.

ROTARY SNOW-PLOW.

1,279,212.

Specification of Letters Patent. Patented Sept. 17, 1918.

Application filed March 8, 1918. Serial No. 221,105.

To all whom it may concern:

Be it known that I, MAURICE J. ACHOR, a citizen of the United States, residing at Marion, in the county of Grant and State of Indiana, have invented certain new and useful Improvements in Rotary Snow-Plows, of which the following is a specification, reference being had therein to the accompanying drawing.

10 The invention relates to rotary snow plows and has for its object to provide a snow plow that may be easily attached to the front and end of a railway engine so that the same may be pushed ahead of the engine and 15 the snow and ice removed from the track. Conveying the snow and ice rearwardly over a conveyer to a hopper, thence depositing the same to either or both sides of the track at any angle desired.

20 A further object is to construct the plow so that it will take the place of the front truck, of the engine or tractor which furnishes its propelling power and also the 25 power for operating the various mechanisms of the plow.

A further object is to provide a pivoted member, pivotally secured to the main frame of the plow, in which a rotary plow is carried and means whereby the pivoted member may be adjusted with relation to the 30 road bed.

35 A further object of the invention is to provide a snow plow, having a pivoted member carrying a rotatable snow cutting member, means for rotating the snow cutting member and a rearwardly extending conveyer pivoted to the rotary snow cutting member and so constructed that the lower end of the rearwardly extending conveyer 40 will remain in its relative position to the rotary cutter when the pivoted member is adjusted at various distances from the ground.

45 A further object of the invention is to provide means whereby the necessary power for operating the various mechanisms of the snow plow will be furnished by the vehicle pushing the snow plow as a whole.

50 A further object is to provide laterally disposed conveyers that may be swung longitudinally in relation to the snow plow when passing through narrow places, such as under bridges.

55 With the above and other objects in view which will appear as the description proceeds, the invention resides in the details of

construction and combination and arrangement of parts hereinafter described and claimed, it being understood that changes in the precise embodiment of the invention 60 herein described may be made within the scope of what is claimed without departing from the spirit of the invention.

Figure 1 is a side elevation of the plow, showing the same attached to the front of a 65 railway engine.

Fig. 2 is a top plan view of the plow showing the same detached from the engine.

Fig. 3 is a longitudinal vertical sectional view through the plow.

Fig. 4 is a sectional view on line 4—4 of Fig. 1.

Fig. 5 is an enlarged detail of a portion of the frame, showing the mechanism for operating the laterally extending conveyers.

Fig. 6 is a perspective view of rail scraper and ice cutter of the pivoted member.

Referring to the drawings, the numeral 1 designates a body frame and pivoted to the front end thereof, by means of the bolt 80 3 is a truck 4 of a conventional form. The truck 4 is provided with wheels 5 adapted to engage and run on rails 6, however it is to be understood that where the plow is used on streets or roads and is being pushed by 85 a tractor, that the type of wheels may be varied. Secured to the end 6 of the body frame, by means of the bolt 7 is a rear truck 8 of a conventional form, this truck is provided with wheels 9 similar to the 90 wheels 5 of the front truck and are adapted to rest upon the rails. The upper end of the bolt 7, is pivotally mounted in a bearing 10, of the portion 11, of a conventional form of engine 12. It will be noted, that the front 95 truck of the engine has been removed and the rear end 6 of the body frame of the snow plow substituted therefor, the rear truck 8 of the snow plow serving as a front truck for the pushing or propelling vehicle.

Pivoted at 13, to the forward end of the body frame 1 is a pivoted member 14, said member comprising arms 16 extending forwardly, also downwardly extending arms 17. The arms 17 being connected by an ice cutting plow 18 adapted to cut the ice, from the track, or where it is packed and hard on the street or road. Rotatably mounted in bearings 19 of the arms 15 are the pintles 20, of the rotary drum 21. The drum 21 is provided with spirally arranged cutter bars 22, which are secured to the surface of the drum

by means of the screws 23, so that they may be replaced with ease. Keyed to one of the pintles 20, by means of the key 24 is a crank arm 25. A pitman rod 26 has one of its ends 5 pivotally secured as at 27 to the crank arm 25, while its other end is pivotally secured as at 28 to a cross head 29, which is in turn guided in its movement in the crosshead guide 30, said guide being secured to the 10 side of the body frame 1 by means of the rivets 31. A piston rod 32 is pivotally secured to the cross head 29 as at 33 and is reciprocated by means of the engine 34, secured to the side of the frame 1 by the rivets 15 35. Steam is admitted to the engine through the steam chest 36, pipe 37 and flexible steam hose 38, which is in turn connected as at 39, to the steam supply pipe 40 leading from the engine to the steam chest 41. Valves 50 and 20 51 are provided controlling the supply of steam to the engine 34. It will be seen, that when the engine 34 is in operation, the rotary snow cutting drum will be revolved and its revoluble movement controlled by the 25 amount of steam supplied to the engine 34.

A gear 52 is secured to one of the pintles 20 and meshes with a gear 53, rotatably mounted upon a stud 54 on one of the arms 15 and secured to said gear 53 and adapted 30 to rotate therewith is a sprocket 55. A sprocket chain 57 extends around the sprocket 55 and sprocket 57^a which is keyed to the shaft 58, of the conveyer 59, said shaft 58 being rotatably mounted in bearings 35 60, of the arms 17. The conveyer 59 comprises sides 60^a, the lower ends of which are pivotally secured to the shaft 58, while its other end rests upon and slidably engages the snow hopper 60^b as at 61, the purpose of 40 which will presently appear. Rollers 62 are secured to the shafts 58 and 63 and extending around said rollers and adapted to be rotated thereby is a conveyer belt 64 for conveying the snow to the hopper 60^b. It will 45 be seen that when the drum is rotated that the snow will be thrown rearwardly on to the moving conveyer belt 64 which moves in the direction of the arrow *a* and that the snow will be deposited in the hopper 60^b. 50 Also it will be seen that ice plowed up by the plow 18 will be forced backwardly upon the moving conveyer belt and then deposited in the hopper.

The adjustment of the pivoted member 14 55 in relation to the ground or surface of the rails is, accomplished by means of jack screws 65, threaded into lugs 66 integral with the body frame 1, their ends 67 engaging lugs 68 integral with the pivoted member 14. Thus it will be seen that when the jack screws are rotated, that the pivoted member 14, will be forced upwardly or allowed to assume a position closer to the ground. If the cutters of the drum should 60 hit an obstruction or object, in the snow,

the pivoted member will pivot upwardly and rise under its power, thereby preventing the breaking of the cutters on the rotating drum.

The hopper 60^b is provided with chutes 69, which discharge the snow to both sides of the machine and on to conveyers 70 and 71. Brackets 72 support the hopper and maintain the same spaced from the body frame. The conveyers 70 and 71 comprise 75 sides 73 and are provided, at their ends, with rollers 74, mounted on and adapted to rotate with shafts 75 and 76, extending around said shafts are belts 77, which move in the direction of the arrows *b*, so that the 80 snow will be discharged to the sides of the machine. Secured to the shafts 75 are sprockets 76, which are rotated by means of sprocket chains 78, which in turn extend around sprockets 79 keyed to shafts 80 85 which rotate in the ends of the conveyers 70 and 71. U-shaped brackets 81, having upstanding arms 82, support inner ends of the conveyers and also have bearings 83 for the shafts 80. Mounted in bearings 84 90 of the body frame 1 are vertical shafts 85, said shafts forming a pivotal point for the brackets 81 and upon which the conveyers pivot when the conveyers are swung at different angles relative to the body frame. 95 Secured to the upper ends of the vertical shafts 85 are bevel gears 86, which mesh with bevel gears 87 which are keyed to the shafts 80. Sprockets 88 are keyed to the vertical shafts 85 and extending around 100 said sprockets and the sprockets 89, keyed to a vertical shaft 90, mounted in a bearing 91 of the body frame 1 are sprocket chains 89^a. Keyed to the upper end of the vertical shaft 90 is a crank arm 92 and pivoted 105 to the end of the crank arm 92, as at 93 is a pitman rod 94. The other end of the pitman rod is pivoted as at 95 to a crosshead 96, slidably mounted in a crosshead guide 97, said cross head being reciprocated by 110 means of a piston rod 98, operated by the engine 99, which is secured to the body frame by means of the bolts 100, steam being admitted to the steam chest 101 of said engine through the branch pipe 102 and 115 under control of the valve 103.

It will be seen that when the crank arm is rotated in the direction of the arrow *c*, that the conveyer belts will move in the direction of the arrow *b* and that the snow 120 from the hopper will be deposited to the sides of the snow plow as a whole. It will also be seen, that the conveyers 70 and 71 will be free to swing at any angle relative to the sides of the body frame, without disconnecting the driving mechanism and that their belts will continue in operation at any angle.

The conveyers 70 and 71 are maintained at any angle relative to the sides of the 125

body frame 1, by means of the pins 104, which pass through apertures 105 in the brackets 81 and through the apertures 106 in the body member 1. It will be seen that 5 the conveyers may be swung to the sides of the frame, when the pins 104 are removed by means of the conveyer driving mechanism.

The invention having been set forth what 10 is claimed as new and useful is:—

1. In snow removing apparatus, the combination with a rotary snow cutter and gatherer, the said snow cutter and gatherer being carried by a member pivoted to the main 15 frame of the machine and inclined conveyer having its lower end pivoted to the pivoted member and having its other end slidably engaging a hopper and means whereby movement will be imparted to the rotary snow 20 cutter and gatherer and inclined conveyer.

2. In snow removing apparatus, the combination with a rotary snow cutter and gatherer carried by a member pivoted to the main frame of the machine, means whereby 25 the snow cutter and gatherer carried by the pivoted member may be adjusted in relation to the ground, an inclined conveyer having its lower end pivoted to the pivoted member and having its other end slidably engaging a hopper and means whereby movement will be imparted to the rotary snow cutter and gatherer and inclined conveyer.

3. In snow removing apparatus, the combination with a rotary snow cutter and gatherer carried by a member pivoted to the main frame of the machine, screw means whereby the snow cutter and gatherer carried by the pivoted member may be adjusted in relation to the ground, an inclined conveyer having its lower end pivoted to the pivoted member and having its end slidably engaging a hopper, said hopper discharging on to conveyers, said conveyers discharging to the sides of the machine, means whereby 40 the conveyers may be swung at different angles to the sides of the machine and means whereby movement will be imparted to the rotary snow gatherer and the conveyers.

4. In snow removing apparatus, the combination with a rotary snow cutter and gatherer, said gatherer being carried by a pivoted member pivoted to the frame of the machine, means whereby the snow cutter and gatherer carried by the pivoted means may 55 be adjusted in relation to the ground, an

inclined conveyer having its lower end pivoted to the pivoted member and having its other end slidably engaging a hopper and means whereby movement will be imparted to the rotary snow cutter and gatherer and 60 conveyer from a machine pushing vehicle.

5. In snow removing apparatus, the combination with a rotary snow cutter and gatherer, said gatherer being carried by a pivoted member pivoted to the frame of a machine and having a transverse ice cutting plow, means whereby the rotary snow cutter and transverse ice cutting plow may be adjusted in relation to the ground, an inclined conveyer having its lower end pivoted to the 70 pivoted member and having its other end slidably engaging a hopper and means whereby movement will be imparted to the rotary snow cutter and gatherer and the conveyer.

6. In snow removing apparatus, the combination with a rotary snow cutter and gatherer carried by a member pivoted to the main frame of the machine, screw means whereby the snow cutter and gatherer carried by the pivoted member may be adjusted in relation to the ground, an inclined conveyer having its lower end pivoted to the pivoted member and having its other end slidably engaging a hopper, said hopper discharging onto conveyers, said conveyers discharging to the sides of the machine, means whereby the conveyers may be swung and locked at different angles to the sides of the machine and means whereby movement will 80 be imparted to the rotary snow gatherer and the conveyers.

7. In snow removing apparatus, the combination with a rotary snow cutter and gatherer, said gatherer being carried by a pivoted member pivoted to the frame of the machine and having a transverse ice cutting plow, means whereby rotary snow cutter and transverse ice cutting plow may be adjusted and limited in its downward movement relative to the ground but not limited in its upward movement, an inclined conveyer having its lower end pivoted to the pivoted member and having its other end slidably engaging a hopper and means whereby movement will be imparted to the rotary snow cutter and gatherer and the conveyer.

In testimony whereof I hereunto affix my signature.

MAURICE J. ACHOR.
